UNITED STATES PATENT OFFICE.

FRANCIS M. GIDEON AND DANIEL RHODES, OF WASHINGTON, DISTRICT OF COLUMBIA.

DESIGN FOR A HANDKERCHIEF.

SPECIFICATION forming part of Design No. 18,462, dated July 17, 1888.

Application filed June 14, 1888. Serial No. 277,156. Term of patent 3½ years.

To all whom it may concern:

Be it known that we, FRANCIS M. GIDEON and DANIEL RHODES, citizens of the United States, residing at Washington, District of Columbia, have invented a new and original Design for Handkerchiefs; and we do declare the following to be a full, clear, and exact description of the invention, such as will enable others skilled in the art to which it appertains to make and use the same, reference being had to the accompanying drawing, and to the letters and figures of reference marked thereon, which form a part of this specification.

The leading features of our design are the rectangular band inclosing the central field, scrolls, and United States flag.

The drawing is a plan view of our design for a handkerchief.

In the drawing, A represents the handker-

chief, on which is formed the azure-colored band of a rectangular shape and designated by the letter B. This band incloses a light-colored field, C, of corresponding shape and crossed at three of the corners by a scroll, D.

What we claim as new is—

A design for handkerchiefs, consisting of the rectangular band inclosing the central field, scrolls across the corners of the field, and United States flag, all substantially as shown and described.

In testimony whereof we affix our signatures in presence of two witnesses,

FRANCIS M. GIDEON.
DANIEL RHODES.
